United States Patent Office

Des. 184,790
Patented Apr. 7, 1959

184,790

STENCIL INKER

Stanley Alexander, Roslyn, N.Y., assignor to Bayberry Products Corp., Stamford, Conn., a corporation of Connecticut

Application May 21, 1958, Serial No. 51,009

Term of patent 14 years

(Cl. D64—11)

Fig. 1 is a top plan view of a stencil inker showing my new design;

Fig. 2 is a side elevational view, the side opposite thereto being substantially similar in appearance;

Fig. 3 is a bottom plan view;

Fig. 4 is a front elevational view; and

Fig. 5 is a rear elevational view thereof.

I claim:

The ornamental design for a stencil inker, substantially as shown and described.

UNITED STATES PATENT OFFICE
CERTIFICATE OF CORRECTION

Design No. 184,790

April 7, 1959

Stanley Alexander

It is hereby certified that error appears in the above numbered patent requiring correction and that the said Letters Patent should read as corrected below.

In the grant, lines 2 and 3, and in the heading to the printed specification and drawings, lines 4 and 5, for "a corporation of Connecticut" read -- a corporation of New York --.

Signed and sealed this 20th day of October 1959.

(SEAL)
